Primary Examiner — Paula Greene(74) *Attorney, Agent, or Firm* — Muncy, Geissler, Olds & Lowe, PLLC(57) **CLAIM**

The ornamental design for a tool handle, as shown and described.

DESCRIPTION

FIG. 1 is a perspective view of a tool handle showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom plan view thereof showing the area upon which a zoom-in view taken and shown in FIG. 9;

FIG. 9 is a zoom-in view thereof; and,

FIG. 10 is an embodiment, perspective view of my design for the tool handle in use.

The broken line is for the purpose of illustrating environment structure and forms no part of the claimed design.
